UNITED STATES PATENT OFFICE.

GEORGE T. SMITH, OF HANNIBAL, MISSOURI.

DESIGN FOR A VEHICLE SIGNAL CASING.

Application filed August 4, 1926. Serial No. 18,592. Term of patent 7 years.

To all whom it may concern:

Be it known that I, GEORGE T. SMITH, a citizen of the United States, residing at Hannibal, in the county of Marion and State of Missouri, have invented a new, original, and ornamental Design for a Vehicle Signal Casing, of which the following is a specification, reference being had to the accompanying drawing, forming part thereof.

Figure 1 is a front or plan view of a vehicle signal casing, showing my new design.

Figure 2 is a side elevation of the same.

I claim:

The ornamental design for a vehicle signal casing, as shown.

GEORGE T. SMITH.
